CLAIM

The ornamental design for a housing for electronics used in a patient therapy system, as shown and described.

DESCRIPTION

FIG. 1 is a perspective view of a housing for electronics used in a patient therapy system, showing our new design, with the broken line showing being for illustrative purposes only and forming no part of the claimed design;

FIG. 2 is a top plan view thereof;

FIG. 3 is a bottom plan view thereof;

FIG. 4 is a left side elevation view thereof;

FIG. 5 is a right side elevation view thereof;

FIG. 6 is an end elevation view thereof; and,

FIG. 7 is an end elevation view thereof, opposite that shown in FIG. 6.
